Primary Examiner — Paula Greene(74) *Attorney, Agent, or Firm* — The Elliott Law Firm;
Douglas H. Elliot; Sarah J. Kelly(57) **CLAIM**

The ornamental design of a headphone device, as shown and described.

DESCRIPTION

FIG. 1 is a side view of a headphone device in accordance with the present invention, the other side is a mirror image of FIG. 1;

FIG. 2 is a top view of the headphone device in FIG. 1;

FIG. 3 is a front view of the headphone device in FIG. 1; and, FIG. 4 is a front perspective view of the headphone device in FIG. 1.

The broken lines showing the remainder of the headphone device are directed to environment. None of the broken lines form a part of the claimed design. The oblique lines indicate a transparent or translucent material.
